UNITED STATES PATENT OFFICE

GALE E. BROOKE, OF MINNEAPOLIS, MINNESOTA

DESIGN FOR A SERVICE BOTTLE

Application filed July 17, 1930. Serial No. 36,378. Term of patent 14 years.

To all whom it may concern:

Be it known that I, GALE E. BROOKE, a citizen of the United States, residing at Minneapolis, in the county of Hennepin and State of Minnesota, have invented a new, original, and ornamental Design for Service Bottles, of which the following is a specification, reference being had to the accompanying drawings, forming part thereof.

Figures 1 and 2 are perspective views of a service bottle, showing my new design.

I claim:

The ornamental design for a service bottle, as shown.

GALE E. BROOKE.
